UNITED STATES PATENT OFFICE.

THEODORE S. WILKIN, OF MILWAUKEE, WISCONSIN.

SAWMILL SET-WORKS.

SPECIFICATION forming part of Letters Patent No. 764,095, dated July 5, 1904.

Application filed November 6, 1902. Serial No. 130,241. (No model.)

To all whom it may concern:

Be it known that I, THEODORE S. WILKIN, residing at Milwaukee, in the county of Milwaukee and State of Wisconsin, have invented 5 a new and useful Improvement in Sawmill Set-Works, of which the following is a description, reference being had to the accompanying drawings, which are a part of this specification.

10 My invention comprises improvements in set-works, whereby greater relative strength of parts, more easy and exact movement of the mechanism, and better resulting application of the power from the force employed 15 are obtained than have heretofore been secured. The mechanism also, among other things, is specifically adapted to secure a greater or less movement of the knees of the sawmill-carriage by means that at the same 20 time provide for certain excess of movement or lost motion within normal movements of the parts in a manner heretofore unprovided for, whereby the knees may be set up exactly a predetermined distance, while other 25 parts of the mechanism may move to an extent not required for merely setting up the knees, thereby providing for movement of greater extent, such greater movement being adapted to be utilized for returning the knees 30 to initial position and also obviously the need 35 for relations between the parts involving exactness of construction and operation, especially between the set-works proper and their steam-cylinder construction and other related mechanism.

The invention consists of the mechanism, its parts, and combinations of parts, as herein described and claimed or the equivalents thereof.

40 In the drawings, Figure 1 is a top plan view of a fragment of a sawmill-carriage on which set-works are shown which embody my improved construction. Fig. 2 is a transverse section on line 22 of Fig. 1 looking toward the right and showing the principal features of my present invention. Fig. 3 is an edge view of the variable rack-arm located centrally in Fig. 2. Fig. 4 is a detail of mechanism employed for operating the variable 45 rack-arm.

My present invention involves improvements in set-works having a general similarity to those shown in my application for patent, Serial No. 94,930, filed February 20, 1902.

In the drawings, A represents a fragment 55 of a sawmill-carriage which is provided with head-blocks B B, having knees C C mounted and adapted to be moved slidably forward and back thereon. A set-shaft 5 has its bearings in the head-blocks and in a bracket 6, fixed 60 on the carriage, and is provided with pinions 7 7, meshing with racks in the under face of the knees C C, whereby by the rotation of the shaft 5 the knees are adapted to be moved forward or set up and to be returned to initial 65 position.

For operating the set-works a motive agent, 70 advisably steam, is preferably employed, and a steam-cylinder 8 therefor is shown, which is mounted on the carriage and is provided with a reciprocating piston having a stem 9, which 75 is connected to a yoke 10, the legs of which travel in guides conveniently at and on the sides of the steam-cylinder. The legs of the yoke 10 are provided with racks 11, that mesh 80 with pinions 12 12, rigid on a hollow shaft 13, having its bearings in brackets 14 14, fixed on the carriage. The shaft 5 for compactness of construction 85 advisably passes through and is fitted loose in the hollow shaft, which is herein denominated the "driven" shaft. The racks 11 on the yoke 10 may be of any desired length, conforming, of course, with the length of the cylinder and its piston-stem, so as to be adapted by the movement of the racks in one direction to rotate the pinions 12 and their shaft 13 one or more complete revolutions at each movement of the rack forward or back. A clutch 15 is arranged to connect the shaft 5 to the driven shaft 13 revolvably, but is commonly disconnected, the clutch being intended to be employed only for connecting the set-shaft to the driven shaft for returning the knees to initial position when a log has been cut up or at any other time, when desired. 95

A rock-shaft 16, mounted on the carriage parallel to the set-shaft 5, is provided with radial arms 17 and 18, projecting therefrom in opposite directions, and rods 19 and 20 connect the radial arms 17 and 18, respectively, 100

to tilting pawls, which pawls at one and the same side of its axis engage with the ratchet-wheel 21, tight on the shaft 5, whereby by the rocking of the shaft 16 the shaft will be rotated limitedly, but always in the same direction.

For connecting the driven shaft 13 operatively to the rock-shaft 16 the driven shaft is provided with a pinion 22, and an arm 23, having a rack engaging the pinion 22, is pivoted at one extremity to a rod 24, which rod at its other extremity is pivoted to the wrist 25^a of a crank-arm 25, keyed on the rock-shaft 16. The rack on the arm 23 is of variable form, there being advisably two portions 26 26^a, that are disposed in lines substantially radially from its pivot 27, and a medial connecting portion 28, and also laterally-extending terminal portions 29 29^a at the other extremities of the radial portions 26 26^a, which terminal portions are each in an arc of a circle described about the pivot 27. These segmental terminal portions 29 29^a of the rack may be extended laterally to any desired length, the arm 23 being correspondingly extended laterally therefor. This variable rack is advisably on the interior surface of a hollowed-out or slotted portion of the arm. The rack is held to engagement with the pinion 22 conveniently by means of a guide-pulley 30, mounted in hangers 31 31, suspended loose revolvably on the shaft 13, one at each side of the pinion 22. The form and disposition of the parts is such that the pulley 30 travels on the exterior surface of the arm opposite the pinion 22 and holds the rack constantly in engagement with the pinion.

The pivot 27 is connected by an anchor-bar 32 to an anchor-pin 33, fixed in a projecting portion of a lever-handle 34, pivoted on the carriage and adapted to be shifted up or down along on a segment-rack 35, mounted at its upper end on a brace 36 and at its lower end connected to the carriage adjustably by a bolt 37, passing through a slot therefor in the segment-rack. The brace 36 at its lower end is pivoted on the carriage at the axis of the lever-handle 34. The handle 34 is provided with spring-held catches 38 38, adapted to take 50 into notches therefor in the rack 35.

The steam-cylinder 8 is provided with steam-ports at 39, controlled by shifting opening and closing valves adapted to admit steam to the cylinder at either side of the piston, as desired.

It will be observed that the arm 23 when moved laterally by the rotation of pinion 22, in mesh with the laterally-extending arcs 29 29^a of the rack, swings about pivot 27 as its axis and will therefore during such lateral movements not move the rod 24 and the crank 25 at all, and also that when the lever-handle 34 is shifted to its upright position the anchor-pin 33 is brought into axial alinement with 65 the wrist-pin 25^a on the crank 25 and that when

the anchor-pin 33 is so in alinement with pin 25^a the arm being moved upwardly and downwardly by the rotation of pinion 22, in mesh with the portions 26 and 26^a of the rack, will merely swing rod 24 about pin 25^a without moving crank 25 and its shaft 16 at all, and hence it will be understood that in use when the arm 34 is thrown up until anchor-pin 33 is in alinement with pin 25^a the shaft 13 can be rotated unlimitedly, shifting the arm 23 up and down without rocking shaft 16 or moving the knees at all, but that when lever-handle 34 is moved down, so as to put the pin 33 out of alinement with pin 25^a, then the works are so set that the rotation of shaft 13 will to the extent predetermined by the adjustment of handle 34 rock the shaft 16 and move up the knees. It should also be observed that this movement of the knees to set them up will be made and completed by one movement of the yoke 10 either forward or back, the shaft 13 being rotated by such one movement of the yoke 10 in either direction to such extent as to carry the rack on arm 23 in mesh with pinion 22 from one end thereof to the other along its entire variable length, the shaft 13 being rotated one, two, or more times, according to the length of the racks 11 11 on the yoke and the size of the pinions 12 12 on the shaft, the pinion 22 being made of such size and the rack on arm 23 being made of such length that the pinion will be caused to traverse the entire length of the rack. These portions 29 29^a of the rack may be extended to any length desired to provide for a greater number of revolutions of the shaft 13 without actuating the rock-shaft 16, thereby providing for a greater rotation of the shaft 13 by the movement of the yoke 10, which can be utilized when desired for rotating the shaft 5, through the clutch 15, to return the knees to initial position. The radial portions 26 26^a of the rack on the arm 23 may be, as shown in the drawings, of such length as by one movement of the yoke 10 to be completely actuated by two rotations of the shaft 13, but, if preferred, may be made shorter, so as to be completely acted on by one rotation of the shaft, or these portions of the rack being of the lengths shown in the drawings an enlarged pinion 22 could be provided which would only act on both of the radial portions 26 26^a of the arm-rack by one revolution of the shaft 13. The results would be the same in the two cases. Of course the extent to which the rock-shaft is rotated, and thereby the extent to which the knees are moved up, depends, as in my former application, on the position that the pivot 33 is set to with reference to crank-pin 25^a, the movement of the shaft 5, and correspondingly the knees, being increased in proportion as the pivot 33 is moved away from alinement with pin 25^a. The shaft 13 always starts from and returns to a home position, which is the position it has when at each end 130

of the racks 11, and at each movement of the piston in cylinder 8 the shaft is rotated to the extent caused by a complete movement of the racks in one direction, and as to whether or 5 not set-shaft 5 is moved thereby at all or to what extent depends entirely on the adjustment of lever-handle 34 up or down and correspondingly of the position of anchor-pin 33 with reference to crank-pin 25^a. It will be 10 understood that when it becomes necessary to return the knees to initial position the pawls on the ends of rods 19 and 20 are lifted out of engagement with the ratchet-wheel 21, and the clutch 15 is made to connect the shaft 13 15 with the shaft 5, and thereupon by moving the yoke 10 back toward the cylinder 8 the shaft 5 is rotated to withdraw the knees, and this may be accomplished by not exceeding one movement of the yoke rearwardly.

20 What I claim as my invention is—

1. In sawmill set-works, a set-shaft adapted by its rotation to move the knees on a carriage, a rock-shaft provided with a crank, means connecting the rock-shaft operatively 25 to said set-shaft, a driven shaft, a pivoted arm having a variable rack engaging said driven shaft, a portion or portions of said rack being so disposed that by the rotation of the driven shaft the arm is swung about its pivot 30 and other portions of the rack so disposed that by the rotation of the driven shaft the arm is moved bodily endwise, a rod connecting said arm at its pivot to a crank on said rock-shaft, and means for anchoring said rod- 35 and-arm pivotal connection adjustably with reference to said crank.

2. In sawmill set-works, a set-shaft adapted by its rotation to move the knees on a carriage, a ratchet-wheel fixed on the shaft, a 40 rock-shaft provided with oppositely-extending radial arms, pawls on said arms severally engaging said ratchet-wheel so as to rotate it in the same direction, a driven shaft provided with a pinion or pinions, a reciprocable rack 45 or racks meshing with said pinion or pinions, an arm provided with a variable rack, said arm being connected to said rock-shaft, another pinion on said driven shaft gearing with said variable rack and adapted by its revolution to swing the arm about its pivot and to move it endwise, and means for adjusting said pivotal connection of said arm to said rock-shaft.

3. In sawmill set-works, adjustable means 55 for taking up excess motion and for communicating a remainder of the motion to a set-shaft, comprising a rock-shaft provided with a crank-arm, a driven shaft, an arm pivoted to an adjustable anchor and provided with a variable rack arranged to engage said driven shaft rotatively, said variable rack being so formed and the arm so disposed that by the rotation of the shaft the arm is moved bodily endwise and may be swung about its pivot,

and means connecting said arm at its pivotal 65 extremity to said rock-shaft operatively.

4. In sawmill set-works, adjustable means for taking up excess motion and for communicating a remainder of the motion to a set-shaft, comprising a rock-shaft provided with 70 a crank, a driven shaft provided with a pinion, a rod connected operatively to said rock-shaft, an arm pivoted to said rod and provided with a variable rack partly in an arc concentric with its pivotal connection to said rod 75 and partly substantially radial thereto, and means for holding said rack in engagement with the pinion on the driven shaft.

5. In sawmill set-works, adjustable means for taking up excess motion and for communicating a remainder of the motion to a set-shaft, comprising a rock-shaft, a driven shaft provided with a pinion and having means for rotating it, an arm connected movably to said rock-shaft eccentrically, an interior variable 85 rack on said arm parts of the rack being in the direction of the length of the arm and parts extending laterally thereof, and means adapted to travel on the arm and hold the rack on the arm in mesh with said pinion on the driven 90 shaft.

6. In sawmill set-works, the combination with a knee-actuating shaft, of a rock-shaft, means connecting the rock-shaft to the knee-actuating shaft whereby the rocking of the 95 shaft will rotate the knee-actuating shaft in one direction, a driven shaft provided with a pinion and with means for rotating it, a crank on the rock-shaft, a rod pivoted to a wrist on 100 said crank, an arm pivoted at one extremity to said rod, a bar connecting said rod and arm at their pivoted connections to a shiftable lever-handle, a variable rack on said arm interiorly, and a pulley-guide mounted in relatively fixed position and adapted to travel on 105 the exterior edge of said arm and hold said rack in engagement with said pinion.

7. In sawmill set-works, the combination with a rock-shaft, a set-shaft, a driven shaft, and reciprocable means for rotating the driven 110 shaft, of means on the rock-shaft for rotating the set-shaft in one direction by the oscillation of the rock-shaft, and other means connecting the driven shaft to the rock-shaft operatively whereby by the rotation of the driven shaft 115 one full revolution or more the set-shaft will during a portion of said shaft revolution be rotated to a certain extent and during another portion of said rotation of said shaft will remain at rest.

8. In sawmill set-works, the combination with a rock-shaft, a set-shaft, a driven shaft about the set-shaft, a clutch connecting the driven shaft to the set-shaft releasably, and reciprocable means for rotating the driven 125 shaft one or more times by each movement in one direction of the reciprocable means, of means connecting the driven shaft to the rock-

shaft operatively adapted to utilize only a portion of the rotation of the driven shaft in actuating the rock-shaft and permitting another portion or portions of the rotation of the driven shaft to be lost on the rock-shaft whereby the driven shaft may be rotated to the full extent of the movement of the reciprocable means in one direction actuating the rock-shaft only limitedly and thereby disposing of the reciprocable means for returning the

knees to initial position by one backward movement of those means when the rock-shaft is disconnected from the set-shaft.

In testimony whereof I affix my signature in presence of two witnesses.

THEODORE S. WILKIN.
